UNITED STATES PATENT OFFICE

VIVIAN W. NEILSON AND CLARENCE C. NEILSON, OF TROUT CREEK, UTAH

LATCH FOR GATES AND THE LIKE

Application filed January 21, 1930. Serial No. 422,311.

This invention relates to a latch for gates and the like, and more particularly for farm gates. Its principal objects are to provide a latch which shall:

1. First. Hold a gate securely in the closed position.

Second. Be proof against manipulation by farm animals, such as horses.

Third. Be semi-automatic in its action and allow a gate to swing in either direction.

Fourth. Be inexpensive.

Fifth. Be simple, durable and not likely to get out of order.

In attaining these objects, we provide 15 preferably a bracket having two legs at substantially right angles to each other, one of the legs being fastened to a post while the other leg serves as a support for one or more pivoted spring-pressed latch members. The 20 latch members are so pivoted that they may be lifted slightly by the operator, thus disengaging the latch from its retaining lug, thereby releasing the gate and allowing it to be pushed open.

To open the gate, the latch is moved in substantially a horizontal plane and is swung to substantially a position where the gate leaves it freely behind ready to again be picked up by the gate in the latter's return movement, whereby the latch is automatically flipped back into the locked position.

In what we term the "single" latch, a single latch member is used which allows a gate to swing only to one side of the post, while in the multiple latch two latches are used whereby the gate may be swung to both sides of the post.

The features of this invention for which the protection of Letters Patent is desired, are collectively grouped in the claims concluding this specification.

In the drawing,

Fig. 1 represents a plan of the single latch in the closed position;

Fig. 2, an elevation thereof, viewed in the direction of the arrow 2, Fig. 1;

Fig. 3, a plan of the multiple latch, one of the latches being partially open and broken away to show a part underneath;

Fig. 4, an elevation viewed in the direction of arrow 4 in Fig. 3, the latch being in the closed position;

Figs. 5 and 6, views in perspective of the single and multiple latches, respectively, in open positions;

Fig. 7, a plan, drawn to a reduced scale, of a latch of modified construction; and

Fig. 8, an elevation viewed in the direction of arrow 8, Fig. 7.

Referring to the drawing, Figs. 1, 2 and 5, the numeral 10 indicates a bracket which may be composed of a substantially horizontal shelf portion 12 integral with an attaching lug 13 which may be fastened to a post 14 by means of bolts 11. The shelf portion 12 may be substantially L-shaped in contour, the stem of the L being indicated at 15 and the bar at 16. Near the extremity of the stem 15 and passing through the same, may be a bolt 17, this bolt at the same time passing through the heel portion 21 of another L-shaped member 18 whose stem is indicated at 19 and whose bar at 20. The L-shaped member 18 forms a latch and is movable in the plane of the shelf 12, being pressed yieldingly thereagainst by a compression spring 24 which may react against the washer 25 held in place by a nut 26.

As shown, the bars 16 and 20 are spaced apart from each other and constitute jaws between which a gate 23, at its front or free end, is normally confined. The gate 23 is hinged as usual at its opposite end (not shown).

In the closed position of the latch, the outer end 27 of the latch stem 19 may extend beyond the bar 16 of the shelf, so as to be conveniently grasped by anyone operating the gate. In this position, the stem 19 of the latch is securely held behind the retaining lug 28 and is prevented from accidental disengagement due to the pressure exerted by spring 24.

When it is desired to open the gate, the latch end 27 is lifted somewhat higher than the top of the retaining lug 28, whereupon a push on the gate, in the direction of the arrow 29, causes the front end thereof to contact the bar 20 and to turn the latch 18 to

substantially the position indicated in Fig. 5, thus permitting the gate to swing open. In closing, the gate swings back, striking the inner edge of the stem 19 somewhat in the manner indicated by the arrow 30. The momentum of the gate causes the latch to be flipped back into the closed position, the bar 20 having meanwhile acted as a follower to the gate until it is again secured in the closed position.

If desired, the latch 18 may be placed below the shelf 12, as indicated by the dotted lines 18—1 in Fig. 5, permitting the latch to operate in a manner similar to that described, with the exception that in the closed position of the latch, the stem 19 will be engaged by the depending retaining lug 31 instead of the retaining lug 28 as previously described. In this case the latch is depressed in opening instead of being lifted.

The double acting lock illustrated in Figs. 3, 4 and 6 functions in general very much like the single acting lock just described. However, instead of having only one latch, the double acting lock has two latches as indicated at 32 and 34. Both these latches are pivoted by means of bolts 35 and 35—1 respectively, to the shelf member 36 which is substantially integral with a bracket member or foot 38 secured to a post 39 by means of bolts 40, and are held in contact with the respective faces thereof by means of the compression springs 37. The shelf 36 in this case, has the plain ends 41.

The bolts 35 and 35—1 extend in opposite directions, and the stems 42 and 44 of the latches 32 and 34 respectively, have their outer ends bent up to form the ears 45 so as to clear the heads of the bolts 35 and 35—1 when the latches are closed. When the latch 32 is closed, it is engaged by the retaining lug 46, and similarly, the latch 34 when closed, is engaged by the retaining lug 47, the retaining lugs 46 and 47 being caused to slip into the openings 48 and 49 defined respectively in the stems 42 and 44.

By opening the latch 32, the gate 50 is allowed to swing in the direction of the arrow 51, and when the latch 34 is opened the gate is allowed to swing in the opposite direction. Whichever latch is opened is served by the bar of the other latch as an abutment stop for the gate. When either latch is open, the other latch in conjunction with the shelf portion 36 may be assumed to constitute the equivalent of the L-shaped shelf portion 12 of the single latch.

The modified construction illustrated in Figs. 7 and 8 may be used when two swinging gates meet each other intermediate the posts to which they are hinged. Here, the front stiles 52 and 53 of two gates meet each other so as to be substantially adjacent, and are held in the closed position by the curved arms 54 and 56 which encircle or embrace

one of the stiles. These arms may have the stems 59 and 60 and be pivoted at 57 and 58 respectively. The arm 54 and the stem 59 form one latch while the arm 56 and the stem 60 form the other latch. The locking features of the latches may be embodied in their respective stems in conjunction with the bracket 61, these being in substantially all respects similar to those of the double acting lock previously described.

If desired, the bracket 61 may carry the integral lugs 62 which may be rigidly secured to the stile 52 by means of pins 63.

While a specific embodiment of our invention is herein shown and described, it is to be understood that various changes could be made therein without departing from the spirit and scope of the invention as defined in the claims.

Having fully described our invention what we claim is:

1. A gate latch, including in combination, two latch members disposed in mutually reversed relation to each other, said latch members having arms curving mutually inward to provide a gate-retaining space, operating stems extending from said curved arms, a bracket disposed to support said latch members, pivots extending through said latch members and said bracket, said pivots located substantially at the juncture between said arms and said stems, and retaining lugs normally extending through said stems, whereby said arms are held in a locked position relatively to said gate.

2. A gate latch, including in combination, a bracket having a shelf, a stop abutment projecting from said shelf, a latch member having a gate-engaging bar spaced apart from and positioned in opposition to said stop abutment, a stem substantially integral with said gate-engaging bar, a pivot member associated with said shelf and said latch member, a spring operative to press said latch member and said shelf together, and a retaining lug projecting from said shelf, said retaining lug being normally in front of said stem.

3. The combination with a supporting member having a shelf portion, of two L-shaped latch members disposed in mutually reversed relation to each other upon said shelf portion, pivots extending through said shelf portion and the heels of the respective L-shaped latch members, said pivots extending from the plane of said shelf portion in opposite directions, and springs on said pivots, said springs being operative to press the respective latch members against the said shelf portion.

4. The combination with a supporting member having a shelf portion, of two L-shaped latch members having stems disposed in mutually reversed relation to each other upon said shelf portion, pivots extending

through said shelf portion and through the heels of the respective L-shaped latch members, and offset ears extending from said stems, said offset ears being disposed to clear 5 protruding portions of said pivots.

5. A latch for gates and the like, including in combination, a bracket having a substantially L-shaped shelf, a substantially L-shaped latch member having its heel pivoted to the -0 stem of said L-shaped shelf so that the bar of the L-shaped shelf shall be positioned opposite the bar of said L-shaped latch member, said shelf and said latch member normally having a surface of contact in common, but 15 being separable from each other in a direction transverse to said common surface, and a retaining lug disposed to normally hold said latch member in engagement with said shelf against angular displacement around the 20 pivot, but to allow angular displacement around said pivot when said latch member is separated from the plane of said shelf a predetermined distance.

6. A latch for gates and the like, including 25 in combination, a bracket having a substantially L-shaped shelf, an attaching lug extending from said shelf substantially transverse to the plane thereof, an L-shaped latch member having its heel pivoted adjacent the stem extremity of said L-shaped shelf, said shelf and said latch member normally having a surface of contact in common, but being separable from each other in a direction transverse to said common surface, and a retaining lug disposed to normally hold said latch member in engagement with said shelf against angular displacement around the pivot, but to allow angular displacement around said pivot when said latch member is 30 separated from the plane of said shelf a predetermined distance.

7. A latch for gates and the like, including 45 in combination, a bracket having a shelf member, an L-shaped latch member having its heel pivoted to said shelf member at one end thereof, another L-shaped latch member having its heel pivoted to the opposite end of said shelf member so as to provide a gate-retaining space between the bars of said latch members, said shelf and said latch members normally having a surface of contact in common, but being separable from each other in a direction transverse to said common surface, and retaining lugs disposed to normally hold said latch members in engagement with said shelf against angular displacement around the pivot, but to allow angular displacement around said pivot when said latch members are separated from the plane of said 50 shelf a predetermined distance.

In testimony whereof, we sign our names
hereto.

VIVIAN W. NEILSON.
CLARENCE C. NEILSON.
